Primary Examiner — Melanie H Tung*Assistant Examiner* — Fitzgerald Butac(74) *Attorney, Agent, or Firm* — Tomlinson McKinstry, P.C.(57) **CLAIM**

The ornamental design for a sprocket with mud relief, as shown and described.

DESCRIPTION

FIG. 1 is a side view of a sprocket showing our new design; FIG. 2 is an edge view thereof; and

FIG. 3 is a front top left perspective view of the sprocket shown in FIG. 1; and,

FIG. 4 is a front top left perspective view of the sprocket shown in FIG. 1.

The broken line showing circular elements is included for illustrating portions of the sprocket and forms no part of the claimed design.

1 Claim, 4 Drawing Sheets(56)
